UNITED STATES PATENT OFFICE.

NICOLAUS H. SCHILLING AND HANS BUNTE, OF MUNICH, BAVARIA, GERMANY, ASSIGNORS TO STETTINER CHAMOTTEFABRIK ACTIENGESELLSCHAFT, FORMERLY DIDIER, OF STETTIN, GERMANY.

GAS-GENERATOR STOVE.

SPECIFICATION forming part of Letters Patent No. 274,829, dated March 27, 1883.

Application filed September 20, 1882. (No model.)

To all whom it may concern:

Be it known that we, NICOLAUS HEINRICH SCHILLING and HANS BUNTE, citizens of the Kingdom of Bavaria, German Empire, and residents of Munich, Kingdom of Bavaria, German Empire, have invented certain new and useful Improvements in Gas-Generator Stoves on the Munich System, of which the following is a specification.

10 This improvement relates to gas generating and burning furnaces, (particularly retort-furnaces for the production of illuminating-gas,) and refers more particularly to the utilization of the heat passing from the furnace. In the 15 generator are generated combustible gases from any desired fuel, especially coke, together with a mixture of hot air and steam, in such a manner that the earthy constituents of the fuel deposit on the grate in the form of a light 20 layer of ash, easily penetrated by air. The steam which is led into the generator is generated by the hot gases continuously escaping from the furnace, and not by the heat of the fuel in the generator, nor from the hot products of combustion, which are drawn from the 25 generator. Air and steam are mixed, and before their entry into the generator they are heated by the heat passing from the furnace. To prevent the formation of slag during the 30 working of the furnace, as also the fusing together of the earthy constituents of the fuel, and to cause the same to deposit in a porous ash on the grate, it is necessary that the amount of the steam be in a certain proportion 35 to the air entering the generator, which proportion depends upon the chemical combination of the earthy constituents of the fuel and the temperature of the mixture of air and steam entering the generator. The furnace is so constructed as to allow the regulation of the proportion of air and steam according to the nature of the fuel, and to allow this proportion to be maintained. Arrangements are provided 40 for this purpose which allow the generation of steam in any desired quantity by means of the heat from the furnace, and to regulate it according to the quantity of air which enters. The operation of the furnace preserves the determined proportion of air and steam permanently and automatically.

In the accompanying drawings, Figure 1 is a vertical section of the furnace in the plane *a b*, Figs. 2 and 3. Fig. 2 is a vertical section of the apparatus in the plane *c d*, Fig. 1. Fig. 3 is a vertical section of the generator in the plane *e f*, Fig. 1. Fig. 4 is a vertical section of the generator in the plane *g h*, Fig. 1. Fig. 5 is a horizontal section of the generator in the plane *i k l m*, Fig. 1.

Similar letters indicate corresponding parts.

The fuel is brought into the generator *V* from above through the neck and rests on the grate *D* at the lower part of the generator. The generator is provided with an opening, *A*, which can be partly or wholly closed at will, 60 and which serves for the entry of the air necessary for gasifying the fuel, which air mixes with the steam rising from the water-trough *B*. The water-trough *B* is covered with a plate, *p*, Figs. 4 and 5. Fig. 5 shows part of the plate *p* near the front of the apparatus removed, so as to expose the water-trough *B* beneath it. This plate *p* prevents ash and other results of combustion from the grate *D* from falling into the trough *B*, and also prevents the vapor from the trough *B*, which mingle with the air, entering under the plate *p*, through the duct *A*, from passing directly up through the grate *D*. The vapor and air pass from the trough *B* at its rear open end, 70 behind the wall *o*, in the direction of arrow 1, Fig. 5, and traverse the channels *C C* in the direction of the arrows, whereby they are heated by coming in contact with the walls, which in their turn are heated by the spent 75 gases passing off through the channels *M*. The vapor and air, after having traversed channels *C*, pass in the direction of arrow 2 into the space above the covering-plate *p*, through the grate *D* and ash-pit *E*, into the fire-shaft of the generator *V*. The gases which are generated by the decomposition of the water-vapor and partial consumption of the oxygen pass through the flues *F* into the burners *G*, where they come into contact with 80 heated air from the channels *N*. The burning gases pass through the spaces *H*, surrounding the retorts in the direction of the arrows, and when spent they pass into the channels *L* through suitable perforations. (Indicat- 85 90 95 100

ed in the drawings by dotted lines, Fig. 2.) The hot spent gases pass from the channels L through the channels M M' M² M³, through the channels M⁴, (whose walls, as already stated, 5 are thus heated and heat the mixture traversing the channels C,) and from M⁴ into the channels M⁵ under the trough B, thus heating the trough into channels M⁶, and thence pass out at the chimney O, Fig. 1. The fresh air 10 for the burners G passes through ducts into the channels N N, Fig. 5, and thence through the channels N' N² N³ N⁴ to the burners G. As the channels M M' M² M³, through which the hot spent gases pass off, lie between the 15 channels N N' N² N³ N⁴, through which the air passes to the burners G, the air while passing to the burners G is heated. The several channels are respectively so arranged that the 20 gases to be heated pass upward, and the cooling gases pass downward and in the direction opposite to that of the gases to be heated, thus utilizing the principle of counter currents. As will be seen, the spent heat of the furnace 25 is first used for heating the air passing through the channels N N' N² N³ N⁴, then for heating the generator-air, and finally for the production of steam.

To secure a more rapid transfer of the heat from the spent gases to the unspent gases, the 30 channels are provided with perforated stones, Figs. 1 and 2, to increase the heat-radiating surface. To equalize as much as possible the pressure in the channels, the smoke-valve for regulating the draft in the chimney is preferably placed behind the apparatus and in the chimney or over the same, instead of at the rear of the generator V.

In the above-described arrangement the water vapor or steam for the operation of the 40 generator is produced by the heat of the spent gases; but as the amount of spent gases is directly dependent upon the mass of fuel gasified in the generator, the quantity of the steam stands in a fixed and permanent relation to the air passing into the generator. Should more fuel be gasified in the generator and the gas consumed in the furnace, a correspondingly greater amount of water-vapor is 45 generated by the spent gases and the relation 50 of steam and air is automatically preserved.

The relative size of the several parts of the furnace are so chosen that a sufficiently large amount of steam can be generated to hinder the formation of slag. To regulate the proportion of air and steam for various fuels according to the constitution of the earthy constituents or according to desired temperatures of the mixture of air and vapor which is to enter the generator, arrangements are made to 55 reduce the generation of steam according to the most advantageous relation. This is accomplished by opening the valve P and allowing cold air to enter underneath the water-trough B, thus reducing the temperature of 60 the spent gases to the extent required. When this condition is attained it is kept up auto-

matically by the function of the stove. After a certain amount of fuel has been consumed in the generator the grate has resting upon it a mass of porous ash, depending for its porosity 70 upon the earthy constituents of the fuel. This ash layer, generated under the influence of steam, is so readily penetrated by air that the regular production of gas is not in the least interrupted, even should a layer of ash of several 75 decimeters in height rest upon the grate. The operation of the generator can be continued without outside interference until the entire ash-pit over the grate is filled with the remains of combustion, which is a period of about twenty-four hours of regular and automatic operation 80 in the case of a furnace such as described, having eight retorts and using coke yielding fourteen to sixteen per cent. ash.

When the ash-pit is filled with the remains 85 of combustion the same are removed as follows: Through the openings Q, which ordinarily are firmly closed, are passed iron rods to support the fuel in the generator. The covers R and S at the face of the furnace are then 90 removed, and the ash which lies on the grate is removed with a crook. This operation takes at most ten minutes, after which the several openings are again closed, and the generator operates regularly until the expiration 95 of the succeeding period of about twenty-four hours, when the ash-pit again becomes filled. The water evaporating from the trough B is replaced by a stream flowing in through the supply-pipe T. On starting the furnace the 100 gas generated, instead of being led through the channels M M' M² M³ M⁴, may be led directly to the chimney O through the channels U, suitable valves being provided for that purpose.

The heating system is here shown applied to retorts. In place of retorts, it can be used for heating in metallurgical works and in generating steam.

As seen from the foregoing description, the 110 steam from the trough B is generated by the heat of the spent gases from the furnace; but in cases where said spent gases possess only a low degree of temperature the hot gases coming directly from the generator may be employed for the generation of steam.

The herein-described apparatus furnishes a satisfactory quality of generator-gas, as the surplus heat coming from the generator is utilized in generating hydrogen and carbonic 120 oxide, and is, so to say, made latent, and thus led to the retorts which are to be heated, and there burned.

What we claim as new, and desire to secure by Letters Patent, is—

1. A gas generating and burning furnace provided with a generator, V, flues F, burners G, with a direct and a return series of channels for conducting the gases to the retort and thence toward the place of discharge, and a 130 water-trough, B, placed beneath the generator-grate and provided with a covering-plate,

as described, said trough being provided with a supply-pipe, T, the whole arranged and adapted to operate substantially as and for the purpose set forth.

5 2. A gas generating and burning furnace provided with a generator, V, flues F, burners G, with a direct and a return series of channels for conducting the gases to the retort and thence toward the place of discharge, a water-trough, B, and a valve, P, for regulating the evaporation from said trough B, the whole arranged and adapted to operate substantially as and for the purpose set forth.

3. In a gas generating and burning furnace, 15 the combination, with the generator, of a water-trough, placed beneath its grate and having a suitable cover, channels C O, contiguous channels M⁴, and channels M⁵, the latter being located beneath the trough, whereby an evaporation is obtained proportioned to the volume 20 of the hot spent gases, substantially as described.

4. The method herein set forth of producing a combustible gas, said method consisting in heating a body of water by exposing it to the 25 products derived from the combustion of said gas, and thereby vaporizing a quantity of water within a given time, which is proportioned to the volume of gas consumed within that time, then mingling the steam thus produced with air, heating this mixture by means of the heated products of combustion, and finally driving it through a body of incandescent fuel, substantially as described.

In testimony whereof we have signed our 35 names to this specification in the presence of two subscribing witnesses.
